US00D871905S

(12) **United States Design Patent** (10) **Patent No.:** **US D871,905 S**
(45) **Date of Patent:** **** Jan. 7, 2020**

(54) **CLOSURE**

- (71) Applicant: **Silgan White Cap LLC**, Downers Grove, IL (US)
- (72) Inventor: **Sungsuk Steve Kim**, Batavia, IL (US)
- (73) Assignee: **Silgan White Cap LLC**, Downers Grove, IL (US)
- (**) Term: **15 Years**
- (21) Appl. No.: **29/583,146**
- (22) Filed: **Nov. 2, 2016**

Related U.S. Application Data

- (63) Continuation of application No. 14/709,198, filed on May 11, 2015, now abandoned.
- (51) **LOC (12) Cl.** **09-07**

CLAIM

I claim the ornamental design for a closure, as shown and described.

DESCRIPTION

FIG. 1 is a top perspective view of a closure, showing my new design;

FIG. 2 is a bottom perspective view thereof;

FIG. 3 is a bottom plan view thereof;

FIG. 4 is a cross-sectional view of the closure, taken along line 4-4 in the direction indicated by line 4-4 in FIG. 3; and, FIG. 5 is a cross-sectional view of the closure, taken along line 5-5 in the direction indicated by line 5-5 in FIG. 3.

1 Claim, 2 Drawing Sheets
